UNITED STATES PATENT OFFICE.

FRANK L. NICHOLS, OF STAMFORD, CONNECTICUT, ASSIGNOR OF ONE-HALF TO MARSHALL HERRINGTON, OF ARLINGTON, NEW JERSEY.

HYDROCARBON-MOTOR.

No. 924,100.

Specification of Letters Patent.

Patented June 8, 1909.

Application filed November 2, 1904. Serial No. 231,051.

To all whom it may concern:

Be it known that I, FRANK L. NICHOLS, a citizen of the United States, and a resident of Stamford, in the county of Fairfield and

5 State of Connecticut, have invented a new and useful Hydrocarbon-Motor, of which the following is a specification.

My invention relates to hydrocarbon motors and more particularly to a motor for 10 using kerosene oil explosively.

The object is to provide a simple, effective and reliable motor of this character for use in connection with automobiles and launches and wherever a compact and economical motor is required.

A practical embodiment of my invention is represented in the accompanying drawings, in which—

Figure 1 is a vertical section taken in the 20 plane of the axis of the shaft, and Fig. 2 is a similar section taken in a plane at right angles to the plane in which Fig. 1 is taken.

The engine here illustrated is of the two-cycle type, its casing being denoted by 1 and 25 including an upright cylindrical portion 2 in which the piston, denoted as a whole by 3, reciprocates.

Surrounding the cylinder 2 is a chamber 4 for the circulation of the cooling liquid as is 30 common.

The crank 6 turns in an inclosed chamber 5 at the base of the cylinder and is connected to the shaft 7 and piston rod 8. This inclosed chamber 5 is connected by a conduit 9 (see Fig. 2) with the interior of the cylinder 2 at a point just above the position which the upper end of the piston occupies when the piston is at the limit of its downward stroke and there is also a conduit 10 connecting the interior of this chamber 5 with the outer air at a point just below the lower end of the piston when the latter is at the limit of its upward stroke.

An exhaust 11 communicates with the interior of the cylinder 2 at a point a short distance above the position which the upper end of the piston occupies at the limit of its downward stroke.

The space between the upper end of the 50 piston when at the limit of its upward stroke and the top of the cylinder is denoted by 12 and forms the vaporizing and combustion chamber. This chamber is provided with a number of depending flanges 13 to increase the extent of crown surface for more rapidly

vaporizing the atomized fuel as it is injected into the chamber and to more thoroughly mix this vaporized fuel with the air in the chamber.

A plug for holding the electric exploder in 60 communication with the interior of the chamber is denoted by 14 and is removably secured in the wall of the chamber as shown in Fig. 1.

The mixture of air and kerosene is forced 65 into the chamber 12 through numerous small openings 15 in the inner end of the hollow injecting plug 16 inserted in the side wall of the chamber 12. These small openings 15 are directed upwardly and inwardly and the 70 end of the plug is permitted to project slightly within the chamber 12 so that the spray from these openings 15 will pass immediately to the depending flanges 13 in the crown of the cylinder and by dashing against 75 them will be very completely broken up and being vaporized by the heat in the flanges in the chamber 12 will be homogeneously intermingled with the air therein.

The interior of the plug 16 is in communication with the chamber 17 through a valve 18, the stem of which is seated in the hub 19 of a perforated diaphragm located within the chamber 17, a light spring 20 coiled around the valve stem being utilized to hold the 85 valve normally closed.

The chamber 17 is in communication with the interior of the pump cylinder 21 through a passageway 22 and access to the interior of said passageway is obtained through an 90 opening 23 closed by a removable tubular plug 24 preferably provided with a stop cock 25.

The casing containing the chamber 17 and the passageway leading therefrom to the 95 pump cylinder 21 and carrying the tubular plug 24 as well as the sight feed reservoir 26, forms the head of the pump cylinder 21 and also forms the seat for the needle valve and its adjusting mechanism for controlling the 100 admission of the hydrocarbon fluid.

The piston 27, which works in the pump cylinder, has its piston rod 28 connected with a crank 29 on a short shaft 30 mounted in the base of the engine casing and operated by 105 means of a gear 31 in mesh with a similar gear 32 carried by the engine shaft 7 so as to cause the pump to make a complete stroke forward and backward with every forward and backward stroke of the engine piston, 110

but set a little in advance of the engine piston to provide for the seating of the valve 18 before the explosion.

The needle valve for admitting the hydrocarbon fluid to the chamber 17 is denoted by 5 33 and is mounted to slide vertically in the base of the chamber 17. It is connected at its lower end with a piston 34 mounted to reciprocate vertically in a chamber 35 formed 10 in the casing at the head of the pump cylinder and having its face in communication with the interior of the pump cylinder through an opening 36 formed in a plug 37 secured in the cylinder head and shouldered 15 at its upper end to form a seat for the coiled spring 38 received within the hollow or recessed lower end of the piston 34 and serving to cushion the piston 34.

The needle valve, its stem and piston having 20 the inertia depending upon their combined weight and being acted upon by force transmitted through an elastic medium, it follows that if the impulses become too frequent or more frequent than the intended 25 rate, the force transmitted in the shortened time is not sufficient to overcome the inertia and operate the valve and hence the speed of the engine is reduced, the valve and its operating mechanism thus serving as a governor.

30 The downward throw of the piston 34 and hence of the valve 33 is limited by the plug 37. The valve 33 seats in the lower end of a rod 39 which passes down through the sight feed reservoir 26, within a sleeve 40 depending from the top 41 of the reservoir 26 and through a sleeve 42 extending upwardly from the base of the reservoir 26 and also through bearings 43, and 44, the former in a depending portion of the base of the reservoir 26 40 and the latter in the upper wall of the chamber 17.

The rod 39 has a channel 45 extending from the valve seat in its lower end upwardly and laterally into communication with the 45 interior of the sleeve 42, the inner wall of which is spaced from the surface of the rod 39 and this sleeve 42 has its wall perforated to open communication between it and the interior of the reservoir 26.

50 The downwardly extending sleeve 40 makes a tight joint with the upwardly extending sleeve 42 and the rod 39 has a screw threaded engagement 46 with the interior of the sleeve 40 so that by turning the rod by 55 means of its hand wheel 47 in the one or the other direction, the rod and hence the valve seat and the valve therein may be bodily lowered or raised within the chamber 17 and the vertical throw of the valve 33 between its seat in the rod 39 and the point where its piston 34 engages the plug 37 will be thereby decreased or increased. It will be understood that this bodily adjustment of the valve 33 which limits its throw, will 65 serve to limit the amount of hydrocarbon

fluid which is permitted to pass it at each stroke.

The sight feed reservoir 26 has its side wall of glass so that the height of the hydrocarbon fluid therein may be observed and the fluid is admitted thereto through a siphon tube 48 which extends from the inlet pipe 49 at the base of the reservoir up through the body of liquid therein and curves over at a point above the surface of the liquid therein so that the liquid passing from the reservoir to the sight feed may be observed as it falls from the end of the tube 48 to the surface of the body of liquid within the feed reservoir.

The operation is as follows: The downward movement of the pump piston 27 tends to produce a vacuum in the upper part of the cylinder 21 which is communicated through the plug 37 to the plunger 34 which, when the vacuum has become powerful enough to 85 overcome the tension of the spring 38, draws the valve 33 downwardly and permits the oil to flow from the reservoir 26 through the channel 45 into the chamber 17. This downward movement and tendency to form the 90 vacuum also assists the spring in drawing the valve 18 to its seat and hence closes communication between the chamber 12 and the chamber 17. As the piston reaches the limit of its downward movement, air is admitted 95 through an opening 50 in the wall of the cylinder 21 to the cylinder space above the piston 27 and on its return movement this charge of air is compressed, the valve 33 closed and the charge of air and hydrocarbon 100 fluid forced past the valve 18 and through the small openings 15 into the chamber 12. The flow of air and hydrocarbon fluid through these small openings 15 atomizes the liquid and projects it in the form of a fine spray 105 against the crown of the combustion chamber where it is vaporized. This flow of air or air and hydrocarbon continues throughout nearly the whole upward stroke of the engine piston thereby mechanically mixing the vapor with 110 the air in the engine cylinder while it is being compressed, resulting in a very homogeneous explosive mixture.

At the moment the engine piston 3 reaches the limit of its upward stroke the explosion 115 takes place forcing the piston 3 downwardly. This downward movement of the piston 3 through the connection of the shaft 7 with the shaft 30 and through the crank 29 and piston rod 28, draws the piston 27 downwardly again to open the valve 33, receive the charge of hydrocarbon fluid and finally the charge of air and to force them through the openings 15 in the pump 16 to produce a new charge for explosion. The downward movement of the engine piston 3 carries the top of the piston below the air inlet and also below the exhaust 11, and, at the same time, compresses the air in the chamber 5 so that this compressed air shoots through the conduit 9 into 130

the cylinder 2 above the piston 3, cleaning therefrom the spent gases and leaving a charge of air above the piston 3 to be compressed by the upward movement of the piston 3 to complete the explosive mixture.

As the piston 3 reaches the limit of its upward movement, the chamber 5 below it is supplied with a new charge of air through the conduit 10.

10 To prevent the heat from the explosion of the mixture in the chamber 12 from unduly heating the piston and burning the lubricating oil, a trouble which has heretofore been common, I form the upper end 51 of the piston 15 independent of the body portion and secure it to the body portion by means of a screw or other suitable fastening 52 extending through it into the hub 53 fixed to the body of the piston by means of two or more 20 wings 54.

Intermediate of the top 51 and the body of the piston, I interpose an annular packing 55 of some suitable non-heat-conducting material such, for example, as asbestos. This prevents the hot top 51 of the piston from communicating its heat to any serious extent to the side walls of the piston so that the oil which is used to cause the piston to run freely within the cylinder, will not become burned 25 and will not gum and thereby prevent the free movement of the piston in starting it after the engine has been, for any cause, temporarily stopped.

The oil is drawn into the sight feeding reservoir 26 through the siphon tube 48 by the partial vacuum formed therein due to the discharge of oil from the reservoir 26 in to the chamber 17 and it follows that this feed may be determined by the adjustment of the 40 rod 39 by means of the hand wheel 47.

In order to start the machine without first heating the wall of the combustion chamber to vaporize the oil, the sight feed reservoir 26 may be provided with a charge of alcohol 45 through an opening closed by a removable cap 56. This alcohol may be used to start the engine and warm it up and as it becomes nearly used, the cap 56 may be screwed into position to close the reservoir 26 air-tight 50 when the oil feed will begin to operate and the engine will continue to run without any further starting operation.

It is to be assumed that the engine casing herein illustrated is to be supported upon a 55 suitable pedestal not shown but which may be of any well known or approved form suitable for supporting the engine shaft and completing the walls of the closed chamber 5.

What I claim is:—

60 1. In an explosive engine, the combination with a combustion chamber provided with flanges depending from its crown and a

piston subject to be actuated by the products of combustion, of an air pump, a conduit connecting the air pump with the combustion chamber, means for admitting a charge of hydrocarbon into said conduit and an atomizing device arranged to direct the atomized hydrocarbon liquid within the chamber against the said depending flanges, 65 the said air pump serving to force the charge of hydro-carbon and air through the atomizing device.

2. In an explosive engine, the combination with a combustion chamber, a piston subject to be actuated by the products of combustion, an air pump and a conduit leading from the air pump to the combustion chamber, of an oil feed valve for admitting oil into said conduit, means for holding the 70 said valve yieldingly seated and a reservoir 75 in communication with said oil feed valve and arranged to receive oil from the supply by the reduction of the air pressure within the reservoir, the said oil feed valve being 80 provided with a piston under the control of the air pump to overcome the inertia of the valve and feed the oil under normal speed whereby the feed of the oil and the consequent speed of the motor is governed by said 85 valve.

3. In an explosive engine, the combination with a combustion chamber, a piston subject to be actuated by the products of combustion, an air pump and a conduit leading from the air pump to the combustion chamber of an oil feed valve a piston connected with the oil feed valve and a spring for holding the valve yieldingly to its seat, the said valve piston being under the control of the air pump through an elastic medium to operate the valve and admit hydrocarbon to the said conduit.

4. In an explosive engine, the combination with a combustion chamber, a piston subject to be actuated by the products of combustion, an air pump and a conduit leading from the air pump to the combustion chamber, of an oil feed valve seated in the air conduit, a piston connected with the 100 valve and under the control of the air pump piston through a passageway independent of the air conduit and means for adjusting the seat of the oil feed valve to regulate the 110 throw of the valve.

In testimony, that I claim the foregoing as my invention, I have signed my name in presence of two witnesses, this 31st day of October 1904.

FRANK L. NICHOLS.
